UNITED STATES PATENT OFFICE.

DAVID MCNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,813, dated March 14, 1882.

Application filed February 6, 1882. Term of patent 3½ years.

To all whom it may concern:

Be it known that I, DAVID MCNAIR, of Boston, in the county of Suffolk and State of Massachusetts, have invented a new and original Design for Carpets, of which the following is a specification.

The nature of my design is fully shown in the accompanying photographic illustration.

The design is composed of, first, a ground richly and elaborately ornamented by figures of various forms, the whole resembling an intricate mosaic work; secondly, sprays of leaves

and flowers scattered over the ornamented ground.

I claim—

The design for a carpet, substantially as shown and described.

In testimony whereof I have signed my name to this specification, in the presence of two subscribing witnesses, this 2d day of February, 1882.

Witnesses: DAVID MCNAIR.

WILLIAM SCHMIDT,
DAVID G. MELVILLE.
